UNITED STATES PATENT OFFICE.

ELARD LUDDE, OF MASPETH, NEW YORK.

BURNER FOR NIGHT-LIGHTS.

SPECIFICATION forming part of Letters Patent No. 405,786, dated June 25, 1889.

Application filed January 22, 1889. Serial No. 297,132. (No model.)

To all whom it may concern:

Be it known that I, ELARD LUDDE, of Mas-
peth, in the county of Queens and State of New
York, a citizen of the United States, have in-
5 ventioned certain new and useful Improvements
in Burners for Night-Lights, of which the fol-
lowing is a specification.

This invention relates to an improved burner
10 for night-lights of that class in which the
burner floats in a body of oil placed on the top
of water in a tumbler or other vessel.

The invention consists of a burner for night-
lights in which a ring-shaped float of cork is
15 provided with a top plate having a central
cross-shaped recess, the prongs of which hold
the taper in position, and with a handle made
integral with the top plate. A diametrical
bottom plate at the under side of the float is
20 provided with raised portions or teats for sup-
porting the lower end of the taper, said bot-
tom plate being attached to the float by prongs
made integral with the top plate, said prongs
being passed through slotted recesses of the
25 bottom plate.

In the accompanying drawings, Figure 1 repre-
sents a side elevation of my improved burner
for night-lights, showing it in position for use
in the tumbler filled with water and a layer
30 of oil. Figs. 2 and 3 are respectively a top
view and a bottom view of the burner, drawn
on a larger scale. Fig. 4 is a vertical central
section of the burner, and Fig. 5 is a vertical
longitudinal section of the top plate of the
35 burner before it is attached to the float.

Similar letters of reference indicate corre-
sponding parts.

Referring to the drawings, A represents a
ring-shaped piece of cork or other light ma-
terial, which serves as a float for the burner.
40 To the top part of the ring-shaped float A is
applied a disk-shaped plate B, which is pro-
vided with an upwardly-bent handle B', made
integral therewith, and with a cross-shaped
recess b at the center, the upturned edges of
45 said recess forming prongs b', by which the
taper or wick is supported in upright posi-
tion when the night-light is to be used. To
the under side of the ring-shaped float A is
applied an oblong bottom plate C, which ex-
50 tends diametrically across the opening of the
float, and which is retained therein by prongs
d, which are made integral with the top plate

B and passed through slots of the bottom
plate C, and then bent outwardly, as shown in
Figs. 3 and 4, so as to retain the bottom plate 55
C firmly in position at the under side of the
float A.

At the center of the bottom plate C, verti-
cally below the prongs b' of the top plate
B, are arranged a number of projections or 60
teats e, which are raised up from the bottom
plate C by suitable dies, and which serve for
the purpose of forming a support for the lower
end of the taper or wick D, as shown in Fig.
4, so that the same is held reliably in upright 65
position while burning. When it is desired
to light the night-light, a taper or wick D is in-
serted into the burner proper and held in po-
sition by being passed into the recess b be-
tween the prongs b' of the top plate B until 70
it rests on the projections or teats e of the bot-
tom plate C. As the lower part of the float is
submerged in the oil of the tumbler, the lower
end of the wick is submerged in the oil and
takes up the same by capillary attraction 75
when the upper end of the taper or wick is
lighted, as customary in night-lights of this
class.

The opening in the ring-shaped float A is
arranged at one side of the center farther 80
from the side at which the handle is arranged,
so as to provide thereby for the proper balanc-
ing of the burner without submerging it to
greater depth at that side at which the handle
is located owing to the greater weight of the 85
same.

The advantages of my night-light are that
the tapers or wicks of the required size can be
used directly without being applied to wooden
disks, as in the night-lights heretofore in use. 90
By dispensing with the wooden disks on each
taper the manufacture of the night-lights is
considerably cheapened and the same packed
and shipped with greater convenience. By
arranging handles the burner can be readily
95 removed from the oil at any time whenever the
oil has to be replenished without requiring
tongs or other devices.

Having thus described my invention, I claim
as new and desire to secure by Letters Patent—

1. A burner for night-lights composed of a
ring-shaped float, a top plate having a recess
forming prongs, and a bottom plate provided
with raised projections or teats below said

prongs for holding the taper or wick in upright position, substantially as set forth.

2. In a burner for night-lights, the combination, with a ring-shaped float, of a top plate having a recess forming prongs and a handle integral therewith, and a bottom plate provided with raised projections or teats below said prongs for holding the taper or wick in connection with the prongs of the top plate, substantially as set forth.

3. The combination, with a ring-shaped float, of a top plate provided with a recess forming prongs, and with a handle made integral

therewith, and a bottom plate having raised projections or teats below said prongs, said top and bottom plates being retained on the float by bent prongs of the top plate passing through slots of the bottom plate, substantially as set forth. 15

In testimony that I claim the foregoing as my invention I have signed my name in presence of two subscribing witnesses.

ELARD LUDDE.
